Ein zentraler Begriff der Soziologie ist dabei der Begriff der Kultur. Kultur ist jedoch kein abstraktes Konzept, das von Menschen und ihrer Kultur abstrakt abstrahiert wird. Kultur ist vielmehr ein Begriff, der die Beziehungen zwischen Menschen und ihrer Kultur beschreibt. Kultur ist also nicht nur ein Begriff, sondern auch ein Begriff, der die Beziehungen zwischen Menschen und ihrer Kultur beschreibt.

UNITED STATES PATENT OFFICE

DRINK MEASURING

576-**AND REGISTERING**

DRINK MEASURING AND REGISTERING DEVICE

210 - Spurlock, Milwaukee, Wis.

Application August 18, 1949, Serial No. 111,020

CL 1 (CL 226-10)

My invention refers to sealed bottle drink dispensers.

The object of my invention is to provide a series of bottles of liquor visibly encased in a sealed cabinet. The inverted bottles each being seated in an electrically controlled stopper having a hollow body. The hollow stopper is provided with upper and lower pairs of valve controlled ports, which ports communicate with a pair of separate filling and discharge chambers of pre-determined area, whereby upon making or breaking the circuit by a manually actuated double switch, a diagonally disposed pair of the upper and lower ports are opened by a pair of valve cores actuated by the magnets to discharge a drink into a glass from one chamber while the opposite stopper chamber is filled from the bottle with a drink to be discharged into a glass upon the next operation of the magnet controlled valve cores, it being understood that a double switch arm is provided with diagonally disposed pairs of contacts which will close the electric circuit to energize the diagonally disposed upper and lower valve cores, whereby said cores are shifted back and forth to alternately fill one chamber while the opposite chamber is discharging into a drinking glass.

Hence, the bartender has no access to the bottle, and when a drink is delivered to a customer, the same is automatically registered by engagement of the double switch arm with a register.

With the above and other objects in view, which will appear as the description proceeds, the invention resides in the novel construction, combination and arrangement of parts, substantially as hereinafter described, and more particularly defined by the appended claim, it being understood that such changes in the precise embodiment of the herein disclosed invention may be made as come within the scope of the claim.

In the accompanying drawing is illustrated one complete example of the physical embodiment of the present invention constructed according to the best mode so far devised for the practical application of the principles thereof.

The drawing illustrates a sectional elevation of a cabinet encasing a hollow stopper for an inverted bottle embodying the features of my invention and diagrammatically illustrating magnet controlled means for actuating the stopper.

Referring by characters to the drawings, I indicates a cabinet having a front glass door 2, which door is locked in its closed position. In practice, the said cabinet 1 is positioned back

Cl. 226—19)

2

of a bar, whereby all bottles displayed therein are visible to customers so that they may, by the brand indicated upon the bottle, select the liquor which they desire.

5 The bottom of the cabinet has fitted therein a series of hollow stoppers 3, it being understood that only one of said stoppers are shown.

10 The upper end of the stopper has extending therefrom a mouth 4, while the lower end has extending through the bottom of the cabinet a discharged nipple 5.

15 The hollow body of the stopper is formed with a pair of chambers 6, 6', which chambers are of an area equaling one drink. The chambers are provided with top and bottom heads 7, 7', respectively, which heads are provided with vertically disposed pairs of upper and lower ports 8, 8', respectively, the upper pairs of ports being in communication with the mouth 4 of the stopper

20 3 and chambers 6, 6', while the lower pairs of ports are in communication with the bottom of the chambers and the discharged nipple 5.

Interrupting each pair of ports 8, 8' of the heads 1, 1' is a transversely disposed channel 9, 9' respectively. Slidably mounted in each of said channels is a valve core 10, 10', the same being reciproacted in its channel, whereby the ports 8, 8' are alternately opened and closed. The said valve cores are provided with longitudinally disposed vent apertures to eliminate blocking of their movement in the chambers. This feature will become more apparent as the description proceeds.

The channels extend through the body of the heads and their open ends have secured thereto upper and lower pairs of magnets 11, 11', whereby the valve cores are moved back and forth when the magnets are energized, which action will be further explained. The pairs of magnets 40 for actuating the valve cores are controlled by a double switch comprising a rocker arm 12 and upper and lower pairs of contacts 13, 13' and 14, 14', respectively, it being understood, as shown in the drawings in full lines, the arm establishes connection between the diagonally disposed upper and lower contacts 13 and 14, 45 whereby the circuit is closed.

An electric energy circuit wire 15 leads from the source of supply to the pair of wires 14, 14' and the second circuit wire 15' leads from the source of energy to the right hand magnet 11' of the bottle stopper. A branch circuit wire 16 extends from the circuit wire 15' to the left hand lower magnet 11' and a branch circuit wire 17 connected to the left hand magnet 11', and the

right hand upper magnet 11 of the stopper. From the last mentioned right hand magnet 11, a wire 17' connects said magnet and the contact 13 of the double switch.

The lower right hand magnet 11' is connected by a circuit wire 18 to the diagonally positioned upper magnet 11 with reference to the lower right hand magnet 11' and the upper left hand magnet 11 is also connected to the switch contact 13' by a wire 19.

Thus, it will be noted that all of the stopper magnets are controlled by the double switch arm 12.

In practice, the necks of inverted bottles are fitted over the mouth 4 of the stopper 3, there being a suitable yieldable ring 20 interposed between the mouth of said stopper and the open neck of the bottle over which it is nestled to prevent leakage.

In practice, an endless belt A is mounted under the nipple 5 of the bottle stoppers for the reception of glasses B, one of which glass is aligned with the bottle designated by a customer from which a drink is desired. Thereafter, the only function the bartender is called upon to perform is that he shifts the switch arm 12 from the position in full lines to the position indicated in dotted lines, whereby the diagonally disposed upper and lower magnets 11 and 11' are energized, it being understood that in this operation the stopper chamber 6' has been emptied. Hence, when the diagonally disposed magnets are energized by closing the connection between the contacts 13', 14', the valve cores will shift their positions from that shown in the drawing to a reversed position, whereby the upper right hand port 8 is open to fill chamber 6' and the upper left hand port 8 is closed with reference to the full chamber 6, and at the same time, the lower right hand magnet 11' will draw the valve core towards it, whereby the lower port 8' in the empty chamber bottom 6' is closed for the reception of a drink, while the left hand port 8' in the full chamber 6 is open to permit the charge of liquor in said full chamber to be delivered into the glass. Thus, when one chamber discharges a drink into a glass, the opposite chamber receives full drink from the bottle; and it should be obvious from the above that when the valve cores are in the position as shown in the drawing that the liquid fills not only chamber 6 but also the left hand side of channel 9 and port 8. Therefore when the valve core 10 moves from the position shown toward the left hand magnet its movement would ordinarily be blocked by the compressing of the liquid in the channel, but by the provision of the longitudinal vent the liquid moves through the core and permits it to travel freely in the channel.

In order to keep a record of the drinks dispensed from a series of sealed bottles, I provide a register 21, which will be actuated by the switch arm 12 in each operation of the device.

In order to save electric current when the apparatus is not in use, I may provide a switch 15', whereby the current will be cut off when the same is opened.

I claim:

- 10 A drink measuring and registering device of the type including a cabinet with a hinged transparent front panel and an endless belt conveyor positioned beneath the cabinet floor comprising, in combination with a sealed hollow bottle stopper having an upper mouth for the reception in the neck of an inverted bottle and a lower discharge nipple extending through the floor of the cabinet and terminating above the conveyor, of a pair of sealed chambers formed in the hollow stopper intermediate the mouth and nipple thereof, upper and lower pairs of valve ports each pair communicating with the stopper mouth, nipple and pair of chambers, a transversely positioned channel interrupting each pair of ports, 15 a valve core reciprocatively mounted in each channel, whereby the associated pair of ports are alternately opened and closed to establish communication between the mouth and nipple of the stopper and a respective chamber, a pair of oppositely disposed magnets carried by the stopper and in alignment with each channel valve core, a manually actuated double switch arm having means cooperating with pairs of diagonally positioned contacts for selectively energizing the diagonally positioned stopper magnets and conductor wires connecting the contacts and the magnets with a source of electrical energy, whereby upon selective movement of the switch arm, a pair of diagonally positioned magnets are 20 energized to shift the valve cores, so that the contents of one stopper chamber is discharged from the nipple into a glass on the endless belt conveyor while the other stopper chamber is filled with liquid from a bottle, and means in each 25 chamber for permitting the liquid in each channel to pass freely from one side of the valve core to the other upon movement of the core.
